UNITED STATES PATENT OFFICE.

GEORGE STANLEY MACDONALD, OF PORTLAND, OREGON.

INTERNAL-COMBUSTION ENGINE.

1,347,817.

Specification of Letters Patent. Patented July 27, 1920.

Application filed November 8, 1918. Serial No. 261,621.

To all whom it may concern:

Be it known that I, GEORGE STANLEY MACDONALD, a citizen of the United States, residing at Portland, county of Multnomah, and State of Oregon, have invented certain new and useful Improvements in Internal-Combustion Engines, of which the following is a specification.

My invention relates to improvements in internal combustion engines, and it consists in the combinations, constructions and arrangements herein described and claimed.

An object of my invention is to provide an engine which will operate economically and efficiently on crude oil, fuel-oil and other liquid fuels.

A further object of my invention is to provide a device of the type described having means for maintaining a supply of fuel, under constant pressure, to an atomizer which discharges into a combustion chamber, the latter being filled with compressed air, and the walls of the chamber being heated so as to ignite the mixture.

A further object of my invention is to provide a device of the type described in which the speed of the engine is rendered constant by automatically reducing or increasing the supply of fuel oil to the combustion chamber through the action of a centrifugal governor.

Other objects and advantages will appear in the following specification, and the novel features of the invention will be particularly pointed out in the appended claims.

My invention is illustrated in the accompanying drawings, forming part of this application, in which—

40 Figure 1 is a vertical section through the engine;

Fig. 2 is a side view of the engine, a part being shown in section;

Fig. 3 is a view of the opposite side of 45 the device;

Fig. 4 is a rear view of the device; and

Fig. 5 is a detailed view of the check valve.

In carrying out my invention I provide a 50 crank case 1, having bearings 2, for the crank shaft 3. The latter is connected by a pitman or connecting rod 4 to a piston 5, of the shape shown in the drawings. The piston is provided with the usual piston rings and has a cut-away portion 6 at its

top to provide an air passage, as herein-after explained.

The piston is designed to operate in a water-jacketed cylinder 7 which is secured to the crank case and which is provided with a communicating passage 8 leading to the crank case, on one side, and with an exhaust port 9 on the opposite side. The top of the cylinder is formed by a plate or casting 10, which has a central recess 11 on the outside thereof. Disposed in this central recess is the base of a combustion chamber 12 which extends through an opening in the top 10 so as to communicate with the interior of the cylinder. This chamber 70 is secured in position by means of bolts, or in any other suitable manner.

Carried by the cylinder wall is a valve casing 13, containing a spring-pressed valve 14, which governs the flow of fuel to an 75 atomizing nozzle 15, projecting slightly into the combustion chamber and provided on its upper side with an opening for admitting the crude oil into the combustion chamber in the shape of a fine spray. The 80 valve stem 16 of the valve 14 projects outwardly, passing through an arm 17 on a rock shaft 18. The arm 17 bears a lever 19 through which the valve stem 16 also passes, the stem being provided with a head 85 20 arranged to be engaged by the lever to force the valve 14 open against the tension of the spring 14^a. The lever 19 is provided with a catch 21, which is designed to engage a portion of the arm 17 so as to hold 90 the valve 14 open, when the lever is operated manually. The valve casing 13 communicates by means of a pipe with a pressure chamber 23, which in turn communicates by means of a pipe 24 with a fuel 95 pump 25. The latter is designed to be operated, while the engine is running, by means of a push-rod 26, slideable in guides 27, through the medium of an arm 28, at the end of a rod 29, extending to an eccentric 30, on the crank shaft 3. A spring 31 is provided to return the plunger of the pump 25 after it has been pushed upwardly by the push-rod 26.

In order to operate the oil pump manually, I provide a lever 32, 105 which may be operated by hand independently of the eccentric. As will be seen from Fig. 2, a relief valve is disposed on one side of the pressure chamber 23, this relief valve being shown at 33 in the draw- 110

ings, while a pressure gage 34 is on the opposite side.

The rock-shaft 18 is operated by means of an arm 35, to which is pivotally attached a rod 36, extending to the eccentric 37. A disk 38 is secured to the shaft 3 and between the disk and the eccentric is a governing device 39 under the tension of a spring 40. This governing device is pivoted to the disk 38, and by increasing or decreasing the tension of the spring, the stroke of the eccentric may be increased or decreased, thereby increasing or decreasing the movement of the rock-shaft 18 and the valve 14 controlled thereby, and thus admitting more or less fuel.

From the foregoing description of the various parts of the device, the operation thereof may be readily understood. Before 20 starting the engine, the valve 41, controlling the pipe 24, and the valve 42 on the pipe 22 leading from the pressure chamber, are opened. The fuel pump 25 is now operated by means of the lever 32. The crude oil 25 is pumped from the receiver (not shown) through the pipe 43 (see Fig. 3), thence through the pipe 24, into the pressure chamber, raising the air confined in this pressure chamber to about 250 lbs. The combustion 30 chamber 12 is now heated by means of an ordinary gasolene or kerosene blow-torch for ten or fifteen minutes. The fly-wheel 44 is now turned backward against the compression in the cylinder, and the lever 19 is 35 hit a sharp blow with the palm of the hand, thus raising the needle valve 45 in the spraying nozzle 15, off from its seat, allowing a fine spray of oil to be forced through the opening 15^x in the upper side of the spraying nozzle, into the superheated air in the combustion chamber, the air being under compression. The mixture of the gas and air is instantly ignited by the hot walls of 40 the combustion chamber, the resulting explosion driving the piston downward on the first stroke. Thereafter the engine operates automatically. On the down stroke of the piston, the air in the crank case is compressed, and when the piston clears the 45 upper end of the passageway 8, the compressed air rushes into the interior of the cylinder, driving out the exhaust gases. On the return stroke of the piston this air is compressed in the combustion chamber. 50 The air enters the crank case through a spring-pressed valve 46, which is screwed in the wall of the crank case and which opens to permit the entrance of the air but closes to prevent the escape of air from the crank 55 case. The governor 39 is set for any desirable speed by increasing or decreasing the tension of the spring 40 which pulls the counter weight toward the engine crank shaft, thereby holding the eccentric in the 60 position allowing the greatest stroke or 65

eccentricity. As the engine crank shaft increases its speed of rotation, centrifugal force causes the counter weight to pull away from the crank shaft, thereby decreasing the eccentricity or stroke of the eccentric, which action, in turn, shortens the stroke of the rocker arm 18, thus decreasing the lift of the needle valve and thereby shortening the period of time that the needle valve remains open. This automatically reduces 70 or increases the supply of fuel oil to the combustion chamber to the extent necessary to keep the speed of the engine constant. 75

When the lever 19 is pushed down against the rocker arm, it is held in position by 80 means of the catch 21 as long as the engine is in operation. The engine may be stopped by releasing the catch 21, or by closing the valve 42 leading to the oil supply. The engine is fired by compression, this being sufficient to keep the walls of the combustion chamber hot enough to ignite the compressed mixture at the proper firing period. After the engine is started the pressure in 85 the pressure tank 23 is kept up to the proper point by means of the fuel pump operated through the eccentric mechanism heretofore described. The relief valve 33 operates to relieve the pressure when it has reached the pre-determined amount. Furthermore, the 90 relief valve is provided with a pipe 33^x to the source of fuel supply, so that any excess amount of fluid will be returned to the source automatically.

It is obvious that the arrangement herein 100 described is equally applicable to the four cycle type of engine, as well as to the two cycle type shown herein. It may be also applied to a multiple cylindered engine, as well as to a single cylinder engine, without 105 departing in the least from the spirit and the scope of the invention.

I claim:

1. In an internal combustion engine, a crank case, a cylinder, a piston disposed within the cylinder, the movements of the piston controlling a communication between the crank case and the interior of the cylinder, a combustion chamber at one end of said cylinder, a spraying nozzle disposed in 110 said combustion chamber, a fluid fuel pump connected with said spraying nozzle, a pressure chamber disposed in the line of connection between said pump and said spraying nozzle, a rock shaft for operating said spraying nozzle, an eccentric for operating said rock shaft, an auxiliary manually operated lever for controlling the communication between the pressure chamber and the spraying nozzle, and a relief valve for preventing the pressure in said pressure chamber from exceeding a pre-determined amount. 115

2. In an internal combustion engine, a crank case, a cylinder, a piston disposed within the cylinder, the movements of the 120

- piston controlling a communication between the crank case and the interior of the cylinder, a combustion chamber at one end of said cylinder, a spraying nozzle disposed in said cylinder, a fluid fuel pump, a pressure chamber connected with said pump, connections between said pressure chamber and said spraying nozzle, means carried by the engine for operating said pump, and auxiliary manual means for operating the pump independently of the engine.
- 5
- 10

3. In an internal combustion engine, a crank case, a cylinder, a piston disposed within the cylinder, the movements of the piston controlling a communication between the crank case and the interior of the cylinder,
- 15

der, a combustion chamber at one end of said cylinder, a spraying nozzle disposed in said combustion chamber, a fluid fuel pump connected with said spraying nozzle, a pressure chamber disposed in the line of connection between said pump and said spraying nozzle, a rock shaft for operating said spraying nozzle, an eccentric for operating said rock shaft, and an auxiliary manually operated lever for controlling the communication between the pressure chamber and the spraying nozzle.
